37 Claims. (Cl. 272—22)

The present invention relates to apparatus for handling scenery, as in a theatre, and has as its broad purpose the provision of a new system for operating scenery in order to change sets at different times, as during a performance.

In typical theatre construction, the stage is provided with scenery that is suspended from lines or cables extending from above, and the scenery is changed by lifting one or more scenery units and lowering others. The region where the raised sets are stored, to be lowered selectively as demanded, is called the "flies" or the "fly-loft." The wings of the theatre are to the left and right of the stage, and the entire area of the stage, above the flies, is covered by a grid or gridiron. The "high iron," which is the supporting structure for the roof over the stage, is spaced above the gridiron sufficiently higher to provide the necessary working space.

For literally centuries there has been a standardized type of construction that is used almost universally at the present time for raising and lowering the scenery. If a single flat is considered as a typical unit of scenery, there will be multiple spaced lines (four lines is usually standard) attached to horizontal pipes or battens supporting this flat. These lines extend upward from the flat to individual pulleys supported by the gridiron, and these lines all extend horizontally to one side of the stage. Each line has a separate pulley, normally where it reaches the gridiron, but all of the lines will extend to a common pulley at the lateral edge of the gridiron. Each common pulley and all the individual pulleys having lines to a batten are in a straight line extending directly crosswise of the stage. Each set of lines extends over its common pulley to a common counterweight. The pulleys for the different sets are in a row at one side of the stage, and the counterweights hang down below them, requiring a vertical operating space that equals the distance that the scenery must be lifted.

Each common pulley is limited almost invariably to four lines so that large and heavy sets may require special treatment. The alignment of each group of individual pulleys transversely across the stage involves complications when sets are to be handled that have substantial depth.

A gallery is usually provided aloft near the common pulleys at the edge of the gridiron, where a stage hand can load weights to balance each new unit of scenery. The space below the common pulleys where lines extend to the counterweights is waste. Operating lines also hang down to stage level for manual operation for lowering and raising the scenery. This represents an allocation of space between the stage and one of the wings that may be needed for other purposes occasionally.

The present invention has as a broad object the provision of new and improved scenery-handling apparatus. A more particular object of the invention is to eliminate counterweights, and the hazard of plummeting counterweights, along with the need for a counterweight loading gallery and the space requirement for travel of the counterweights. A further object of the invention is to enable free selection of the scenery-handling station, completely without restriction in relation to the line-operating mech-

anism. A still further object is to clear the space at the lateral limits of the stage formerly allocated to scenery operating apparatus, to make it freely available for other use.

5 An additional object resides in the provision of novel apparatus that eliminates the manual operation of pulley-operating lines, by substituting remote-controlled electrically powered apparatus. Through this feature of the invention, the change in scenery can be accomplished at greater speed (a most important consideration in some dramatic presentations) and it may be accomplished at an architecturally convenient location. The simple operation of electrical controls is effective to shift any desired sets as fast as desired, limited only by the motor power and the strength of the lines and of the sets.

10 In another aspect, a basic object of the present invention is to provide novel highly flexible apparatus for handling scenery. The novel stage organization made possible by this aspect of the invention is not restricted and confined to the previous requirement of each group of lines extending to a common pulley, nor to the use of any particular number of lines for a unit of scenery nor to the previous requirement that the individual pulleys for lines of a group are to be in a straight line extending across the stage.

15 An important feature of the present invention resides in the use of electric motor driven winches for individual lines to a set and in the coordination of such motors. Through this basic departure from standard practice, 20 each motor and each winch can be located wherever may be convenient. The control apparatus may also be located at any desired position. This flexibility at once opens up the possibility of broad architectural change from conventional back-stage theatre designs. The

25 side of the stage previously reserved for counterweights, operating lines, and the associated common pulleys can be made open and clear, free for new uses. The counterweight loading gallery is also eliminated, and the procedure of balancing the weight of the set with counterweights is also eliminated. Electrically coordinated motor-driven winches are used that are individual to each line; and there is no longer any need for lines extending inflexibly from respective pulleys in the gridiron toward the common pulleys, nor is there any arbitrarily limited number of lines that may be operated in unison. The invention makes it possible for any line to extend in any convenient direction to any available winch. A related feature of the invention resides in the provision of supports for individual sheaves virtually anywhere that 30 may be desired, without the restriction heretofore of requiring individual pulleys of a group of lines to be nicely in line across the stage.

35 Further features of the invention reside in the provision of rows of firmly supported electric-motor driven

55 winches at any convenient locations above the flies, as for example spaced along the rear of the stage or at the side of the stage or across the front of the stage, or at all such places. No longer it is necessary for all of the lines from a given piece of scenery to extend all the way across the stage to a common pulley. With the present system, each line can extend to the nearest convenient accessible motor-driven winch. Each line need be no longer than necessary to reach the closest available winch. With the new system a line from a scenery element 60 near the center of the stage can extend to a winch at the rear, and lines from the same scenery element that are near the sides of the stage can extend to winches at the sides of the stage, all of the winches for handling a stage set being coordinated electrically.

65 With the novel system it will be apparent that the lines extending upward from the scenery to pulleys or sheaves will usually extend from those sheaves in various direc-

tions toward the motor driven winches disposed about the stage, above the flies. As will be seen from the detailed description below of the illustrative embodiment of the invention, any desired number of winches can be coordinated and are effective to share the weight of a set during raising and lowering operations. Further, lines can extend upward from any fastening point on a stage set, whether it be flat or complicated so as to extend both across the stage and having prominent front-to-back depth.

Additional features of the invention relate to the electrical controls provided. These include provision for automatically limiting the extent of raising and lowering of the various sets, as well as for reducing speed as each limit is approached, while maintaining proper coordination of the winches; in the selection of each group of winches; and the provision of means for concurrent operation of two groups of winches for simultaneously raising one stage set and lowering another.

The foregoing objects and features of the invention are accomplished in the illustrative embodiment described in detail below. In this embodiment, briefly, a series of winches are provided for the individual lines extending to sets or units of scenery. The lines for handling each set extend to physically independent winches which are electrically coordinated. Each winch handles one line. Each winch is driven by an individual electric motor. The control apparatus enables any combination of winches that may be identified with a particular set to be connected for common control and energization. Two controlled power sources are provided and selective controls enable each source to be switched to each successive group of motors while the other source is applied to any other selected group of motors for concurrent operation but separately controlled as to speed and direction.

A feature promoting sustained coordination resides in the use of synchronous type motors for the winches, and controlled-frequency sources of alternating current for speed control of all winches operating a unit of scenery. Electric motors of other types capable of sharing the load of a set can alternatively be used in applying certain broader aspects of the invention.

As a detail of specific importance, the winches are ideally of a form where the length of line taken in or paid out per motor rotation is constant, and where the point at which the line reaches its winch is constant, so that, with equal motor rotations and uniform handling of the several lines of a set, initially established sharing of the load is maintained.

With the foregoing background, the features of the illustrative embodiment described below will be readily appreciated, and from this description additional objects and features of novelty will become apparent. The illustrative embodiment of the invention is shown in the accompanying drawings forming part of this disclosure. In the drawings:

Fig. 1 is the cross section of a portion of a theatre showing the stage thereof, to which the invention is applied;

Fig. 2 is a vertical fragmentary cross-section along the line 2-2 in Fig. 1, drawn to a larger scale;

Fig. 3 is a plan view of the structure in Fig. 2;

Fig. 4 is the side elevation of a typical novel winch and related structure shown in Figs. 1 to 3, Fig. 4 being drawn to larger scale;

Fig. 5 is an elevation of the winch in Fig. 4 viewed from the right thereof;

Fig. 6 is a top plan view of the winch in Figs. 4 and 5;

Fig. 7 is a fragmentary transverse cross-section along the line 7-7 in Fig. 5;

Fig. 8 is an enlarged detail of the sheave and sheave support in Fig. 4, the section being taken along the line 8-8 in Fig. 4;

Figs. 9a, 9b and 9c are the wiring diagram for control and coordination of a system of winches illustrated in the other drawings; and

Fig. 10 is an elevation of conventional scenery handling apparatus view as per Fig. 2.

Referring first to Fig. 10 there appear certain typical elements of conventional scenery-handling apparatus, supplementing the brief description above. Such apparatus is widely used and has been in use for several centuries. (The numerals used here are primed numerals corresponding to those used in the description of apparatus in Figs. 1 to 9 which follows.) In Fig. 10 the stage 10' has a flat 24' carried by lines 26' which extend over pulleys 29' carried by the grid 32'. All 15 of the lines 26' extending from a single scenery unit 24' extend to a common pulley 20' and from this pulley to a common counterweight 19 which counterbalances the entire load of the scenery unit 24'. Pulley 20' is suitably supported from wall 22', this wall extending down 20 to the stage, or to a point close to stage level. Wall 22' additionally carries a gallery 21 close to the grid level, where a supply of counterweights is stored and where the sets, when being installed, are counterbalanced. Weights are added to the group of lines 26' until the 25 scenery unit is accurately counterbalanced. Thereafter, the weights are lowered and the set is elevated, or the converse, by means of an additional line 27 which rotates pulley 20' in either desired direction.

The individual pulleys 29' guiding the group of lines 30 26' are distributed along a line directly across the stage, that is, parallel to the front of the stage. It therefore becomes necessary to provide scenery of such design that can be supported by this arrangement of lines. Each 35 common pulley 20' can accommodate four lines, so that no more than this number of lines can be used for an individual set, regardless of its shape, size or weight. Pulleys 29' are supported on rails extending front-to-rear above the stage at a wide separation, which is a further limitation on the usefulness of the system. It 40 is feasible to adjust the position of each pulley 29' perpendicular to the view, toward and away from the front of the stage; but all of the pulleys together with pulley 20' are required to be adjusted so as to remain in line.

In view of the requirement that all of the lines 26' attached to a given flat 24' shall move together, they must 45 all be operated by the same pulley 20' and therefore, if a single stage set extends all the way across the stage, the line to the most distant part of the scenery must also extend all the way across the stage, from the most 50 remote vertical line to the pulley 20'.

The common pulleys, counterweights and operating lines, being located only at the side of the stage, preempt the space there which might be used for other purposes. The walls 22' also support the weight-loading gallery 21.

55 The grid 32' must be strengthened as by tie rods 33 extending to the high iron 18' to support the pulleys 29' and the scenery load.

This brief description of the typical standard apparatus for handling stage scenery can be extended for better 60 appreciation of what is involved by reference to standard works on this subject as for example, that by Cole, Burris-Meyer entitled "Scenery for the Theatre."

Referring now to Figs. 1 to 3 inclusive, the stage 10 of a theatre is illustrated, having a front wall 12 in which 65 there is formed a proscenium 14 through which performances are witnessed, and a rear wall 16. The roof of the stage is supported by so-called "high-iron" 18 being usually a number of parallel I beams extending from the front to the rear of the stage. A series of winches 20 are shown 70 extending along the front and back walls of the stage, and also against side walls 22 (Fig. 2) depending a short distance from the high iron 18. One such side wall 22 depends from the high iron at each side of the stage, leaving the space below these walls 22 at both sides of 75 the stage completely free and clear. This is the space

that heretofore has been occupied by the counterweights and by the operating lines 27 (Fig. 10). Further, no counterweight loading is needed in the full application of the present invention.

In Figs. 2 and 3, one element of scenery 24 is shown at stage level and another element 26 is shown raised into the flies. An additional stage prop 28 is shown carried by a single line extending to its particular winch. Seven of the winches in Figs. 2 and 3 are designated 20A, 20B . . . 20G. Winches 20A, 20C and 20E are connected by respective lines to the set or scenery unit 24 whereas winches 20B, 20D and 20G have lines extending to the raised set 26. Winch 20F extends to scenery element 28.

Certain of the winches on wall 22 are seen in Fig. 3 to have lines extending to scenery, and these winches are located approximately where the common pulleys of conventional apparatus previously were supported; but other winches designated 20A through 20F are shown carried by the rear wall, an area previously ignored insofar as the scenery handling apparatus is concerned. With the present arrangement as shown, evidently comparatively short lines can be used (insofar as their horizontal extent is concerned). If the line 26 extending from the winch 20E to a point above scenery element 24 is considered, its length is obviously much shorter than would be needed if that line were required to extend all the way to a common pulley at the side wall 22. The difficulties arising under previous practice become much more serious when it is considered that the right hand extremity of each element of scenery, omitted from Figs. 2 and 3 might very well extend all the way across the stage.

The lines extending from the winches 20 extend horizontally (at a small incline) to respective sheaves 29 which are carried by members 30, conveniently formed of steel, T-shaped in cross section. Members 30 are either directly secured to the high iron 18 or are carried by frame members 32 which in turn are carried by the high iron.

The gridiron 32 is provided in the present illustrative embodiment of the invention at some distance below the high iron. This gridiron provides a platform over which personnel can walk in setting up the sheaves 29 and the various lines from the winches to the scenery units below. The gridiron has a number of channels forming passages 34 between which the lines can freely extend, the remainder of the gridiron furnishing walking area. Passages 34 extend from the front to the rear of the stage, in the illustrative embodiment. These need not be made very close to each other as, for example, at 4-foot intervals.

As will be understood from the detailed discussion of the wiring diagram, the various winches having lines to individual scenery units are electrically coordinated and they function in exactly the same way as the common pulleys and counterweights that previously were utilized for handling a scenery unit. Previously numerous advantages flow from the use of independent motor drives illustrated. Previously no more than four lines (as a practical limit) could be handled by any one pulley and counterweight unit. Consequently a large or heavy element of scenery, or one which has a very great extent across the stage, might have to be subdivided so as to be separately handled and operated by two or more separate pulley-and-counterweight complements. In the present instance as many winches and lines as may be considered appropriate can be assigned to any one element or related elements of scenery. It is entirely feasible to operate multiple separate elements of scenery forming part of a single set by coordinated winches. Thus, element 28 which is part of the lowered set can be raised and lowered by its winch 20F, which winch can be electrically coordinated with the three winches 20A, 20C and 20E having lines to the scenery unit 24 that is also lowered at stage level. In this way, any selected and

coordinated group of scenery elements stored in the flies above the stage can be lowered to stage level with a single control and in a single quick powered operation. All those elements of the set can likewise be removed to the flies simultaneously. This system makes possible high speed of change, which can be of critical importance in preserving the mood and timing in some dramatic performances. Comparable speed could hardly be realized with the previous standard scenery-handling apparatus.

The winches, the high iron, the sheaves 29 and the sheave supports 30 are shown in greater detail in Figs. 4 to 8, inclusive. In Figs. 4 and 8 the high iron 18 carries the parallel elements 30 of T-shaped cross-section extending along lines front-to-rear of the stage, and this in turn supports sheaves 29. A series of holes 30a are formed in members 30 at convenient intervals, every three inches for example. In this way a sheave can be located at any position required by the contour of the scenery, and the different sheaves having lines extending to different parts of the scenery can be located at different distances from the rear of the stage. This feature is of particular importance to accommodate deep sets, of relatively complicated configuration, or sets that are required to extend slantwise across part of the stage.

The sheave 29 is carried by a U-shaped bracket 34 (Fig. 8) which has holes in its side walls, through which spring pressed pins 36 extend. These pins may be withdrawn from the holes in members 30 by grasping knobs 36a forming part of these pins. Springs 36b bias the pins to the right in Fig. 8 so that when released, pins 36 project through the holes 30a in the sheave-supporting members 30. Thus each sheave 29 can readily be located at any point above the stage, front-to-rear, that may be convenient or required.

U-shaped member 34 has a bearing 38 that allows the pulley 40 to rotate about a vertical axis. This is desirable when it is considered that a line from a sheave to a winch frequently extends at an angle to the front-to-back extent of member 30 over the stage (see Fig. 3 for example).

The winch itself is shown in elevation in Figs. 4 to 7. The winch is carried by a pair of fixed brackets 42 on a wall or other suitable support and by a movable frame 44 that is movable on axially aligned pivots 46, conveniently shock-mounted, allowing the frame 44 to swing about a vertical axis. This swinging enables a guide pulley 48 carried by the frame 44 to move into alignment with the sheave 29 to which the set-supporting line 26 extends.

A threaded bearing or nut 50 is carried by frame 44 at its lower extremity and at the upper extremity there is a motor 52 which, through a worm 54 and a worm wheel 56 (Fig. 5) drives shaft 58. The upper portion of shaft 58 is splined and the bottom of it is seen to be threaded. Worm wheel 56 is restricted against vertical shift by fixed bearing plates 44a. In this way, as the motor rotates shaft 58 through the worm drive described, the lower portion of shaft 58, in rotating in threaded bearing 50, is also forced to travel up and down axially. Shaft 58 carries a drum 60 which has a helical groove in it, of the same pitch or number of threads per inch as the lower portion of shaft 58 and consequently drum 60 travels up and down in relation to guide pulley 48 at the same rate that the line-receiving grooves on drum 60 travel. Worm wheel 56 has passages allowing the splined portion of shaft 58 to slide up and down in relation to it (portions 48a preventing axial travel of the worm wheel 56 in relation to the worm drive 54).

In addition to motor 52, bracket 44 also supports a transmitter synchro 62 having a sprocket 64, and chain 66 to couple it by sprocket 68 to shaft 58. Bearing plate 44b prevents shift of sprocket 68 away from upper bearing plate 44a. In this way, synchro 62 generates a signal which is transmitted to a receiver synchro (described

later) to indicate the rotational position of shaft 58 and, accordingly the axial position of drum 60.

The mechanical operation of the winch in Figs. 4 to 7 may be readily understood. When tension is developed in line 26 extending from sheave 29 to guide pulley 48 of the winch, that guide pulley is lined up with the sheave. If the selected winch is not in line with T-shaped sheave hanger 30, frame 44 of the winch swings about its pivot 46 so as to bring pulley 48 into alignment with its sheave 29. (Before line 26 is tensioned, pressure roll 61 shown in Fig. 7 prevents loosening of the line). Operation of motor 52 rotates shaft 58 through the worm drive 54-56, and line 26 winds or unwinds, depending upon the direction of motor drive. Drum 60 is gradually raised or lowered by the threaded lower portion of shaft 58 operating in threaded bearing 50, in order that the grooves of drum 60 will be in proper relation to receive or pay off the line 26. The provision of the worm drive is important, in that this drive prevents tension in line 26 from rotating shaft 58, that is, the worm drive is self-locking and is not capable of mechanically reversed operation. Rotation of the worm wheel 56 cannot take place in a way to drive the worm 54. This worm drive 54-56 is in one-way drive in the sense that mechanically the member 54 is always the drive member and member 56 is the driven member. In this way, the weight of the set carried by line 26 is ineffective to drive the worm gearing in reverse so that, when motor 52 is idle, the position of the set is fixed. The term one-way mechanical drive is used in referring to the driving member in relation to the driven member, and not to the rotational sense. Motor 52 is of a type to be electrically reversible for either rotational direction, for winding up or paying off a desired length of line 26.

In the course of reeling in or paying out some of line 26, because drum 60 moves to maintain a common winding point at guide wheel 48, the distance from the winding point of the winch to the sheave 29 is constant. It will also be recalled that the vertical portions of lines 26 are parallel and are moved in equal increments by the coordinated winches. Hence all of the winches maintain their respective shares of the set load regardless of vertical position of the set and regardless of the random angles (note Fig. 3) that may result in the choices of winches for each set.

Drum 60 may, for example, be of four-inch diameter and 12 inches long, with close-spaced grooves for receiving $\frac{1}{8}$ diameter steel cable. Such a drum can store 90 feet of cable.

Synchronous electric motors 52 for the various winches are operated and coordinated by remote control, from a console at a convenient location, preferably at a point from which full view of the stage may be had. The wiring diagram of that portion of the illustrative system that is installed aloft with the winches is shown in Fig. 9a; the wiring diagram of the console is in Fig. 9b; and the wiring diagram of the power supply and its associated controls appears in Fig. 9c.

The system includes two separate sources of power, so that it is entirely feasible to raise one set and simultaneously lower another set, each at its own rate and each stopping independently, as required. This feature is highly desirably in dramatic situations where quick change of sets is all-important.

In Fig. 9a, nine winches 20 are shown, with a suitable number of these including transmitter synchros 62 and the others, labeled 20a, lacking these synchros. Each motor 52 is connected by a first relay 80 to power lines 82 that are connected to a controllable alternator 84 (Fig. 9c) suitably located in a sub-stage installation, for example. Motors 52 can, alternatively, be connected by respective relays 86 to the power lines 88 from another remotely located alternator 90. A common mechanical drive motor 92 operates alternators 84 and 90 through electro-dynamically controlled drive couplings,

94 and 96, respectively. This form of drive, the dynamic couplings 94 and 96, may be compared to a clutch which may be either effectively disengaged so as not to drive its generator at all, or it may not slip at all so as to drive its generator at the full speed of motor 92 or the dynamic coupling may "slip" controllably, to provide any desired rate between dead stop and full motor speed. The speed of the alternator determines the frequency of its output and this determines the speed of each synchronous motor 52 connected to it. Dynamic couplings 94 and 96 have their control devices 98 and 100. These dynamic couplings and their controls are well known and their details, forming no part of this invention, are not herein described. In one form, the dynamic coupling may be an eddy current clutch whose control gradually increases the eddy current field to increase the tightness of coupling. Thyatrons with adjustable grid-bias circuits are useful to control the eddy current.

Each dynamic coupling control unit 98 and 100 has a control wire 102, which wires may be joined together. Unit 98 has a maximum speed connection 104 and a minimum speed connection 106, whereas dynamic coupling control unit 100 has its maximum control wire 108 and its minimum speed control 110. A potentiometer 112 (Fig. 9b) is provided which enables manual selection of any desired speed between minimum and maximum of generator 84 and similarly a potentiometer 114 is provided for enabling adjustment of the speed of operation of generator 90 to any value between its minimum and maximum speeds as controlled by wires 108 and 110.

Each alternator 84 and 90 can be connected to its respective power lines 82 and 88 for operating the winch motors 52 in either rotational direction. This depends upon the phase rotation of the motor, in relation to the connections of the generator to the line. Either phase relationship can be established by selecting the appropriate motor starter 116 or 118. Motors 52 are all phased for like rotation when connected to lines 82. Starter 116 may be phased to connect the alternator 84 to lines 82 for raising the sets, and starter 118 is then oppositely phased to connect alternator 84 to lines 82 for lowering the sets. Each motor starter functions for all the motors connected to the three-phase lines 82 or 88. Similarly three-phase generator 90 can be connected to its power line 88 by starters 120 and 122, respectively, for either raising or lowering the sets operated by motors connected to that power line. Starter selecting switch 124 is provided in the console (Fig. 9b), having one section 124a connected by wire 116a to the "Up" starter 116 and another section 124b connected by wire 118a to the "Down" starter 118 at the output of alternator 84. Similarly the starter selecting switch 126 is provided in the console, having one section 126a connected by wire 120a to the "Up" starter 120 and another section 126b connected by wire 122a to the "Down" starter 122 at the output of alternator 90. These starters connect power to all of the motors which, at any given time, are connected to the respective power lines 82 and 88 by the various relays 80 and 86 (Fig. 9a).

Switches 124 and 126 are three-position switches so as to have a neutral position, an "Up" position and a "Down" position. Normally these switches are in their neutral position. Switch 124 is, however, shown in position to operate the motors and winches of the generator 84 and its power line 82 in the "Up" direction whereas switch 126 is shown in position to operate the motors 52 connected to lines 88 of alternator 90 in the "Down" direction. Normally these switches 124 and 126 are moved away from their neutral position for operating the respective starters only after selection of the various motor-winches had been effected as will appear below.

In the control console, there is a receiver synchro 128 that is connected by wires 129 to a respective transmitter

synchro 62. Single phase power is continuously fed to the transmitter synchros 62, but switches 130 can discontinue the supply of single phase power to the receiver synchros, when they are not required to function. Each synchro causes a travelling dog or switch operator 134 to move along the threaded shaft 132 in synchronism with the travel of the end of a line operated by the winch that also drives the transmitter synchro 128. When switch operator 134 is near its lower limit, the scenery element carried by the related line is also near its lower limit and conversely when switch operator 134 is near its top limit then the scenery carried by the winch that operates the related transmitter synchro 62 is near its upper limit, in the flyloft above the stage. This operation occurs, naturally, when switch 130 is closed so that the transmitter and the receiver synchro operate in synchronism. When switch 130 is open and synchro 128 is idle, diagrammatically illustrated handle 135 can be used to manually operate shaft 132 and shift the dog 134 to any desired position, in setting up new scenery.

Associated with threaded shaft 132 and travelling dog 134 are switch bases 136 and 138, which are suitably adjustable in relation to shaft 132 and in relation to each other. The "Up" stop limit switch 140 is carried by the switch base 136 and the "Down" limit switch 142 is carried by the base 138. As will more clearly appear below, switches 140 and 142' are in series respectively, with contacts 124a and 124b of direction control switch 124 and with one of the starters 116 and 118 when alternator 84 is selected. This series circuit is, however, incomplete until selector switches described below have been operated. Bases 136 and 138 also carry anticipatory rate-control switches 144 and 146 respectively, having contacts 144a which are normally open and 144b which are normally closed as well as contacts 146a that are normally open and 146b which are normally closed.

In the operation of shaft 132, the travelling dog 134, moving from the center, first engages rate control switch 144 or 146 (depending upon the travel direction) and regardless of which rate-control switch is first operated the control unit 98 is effective to cut down the speed and output frequency of alternator drive effected by dynamic coupling 94 or 96, as the case may be. As a result, winches energized by the alternator may change in speed from 2 feet per second to two inches per second. Bases 136 and 138 are adjusted so that this occurs during the final 3 feet of travel of each set. Scale 147 associated with each screw 132 provides indication of the position of the related set. As will be understood more fully below, a separate assembly 132 . . . 147 is provided for each set that is to be handled separately.

Travel of dog 134 beyond either rate control switch 144 or 146 is effective to open limit switch 140 or 142 (depending upon whether the operated winches are operated for raising or lowering a set) and opening of either of these switches (with the corresponding contacts 124a or 124b closed) is effective to stop the drive for the generator 84 or 90 by the motor 92, through the dynamic coupling 94 or 96.

In the foregoing description it has been presumed that a group of motors 52 are connected to the bus 82 supplied by generator 84 through one of the starters 116 or 118 depending upon the setting of direction control switch 124. Selective controls are provided which enable the switches 140, 142, 144 and 146 to be connected in control relation to the control unit 98 of generator 84 (thereby controlling the power delivered to bus 82) or, alternatively, for enabling the switches 140, 142, 144 and 146 to be connected to the control unit 100 of generator 90, thereby to control the power delivered to the three-wire bus 88. Theoretically any set of these rate and limit switches could be connected simultaneously to either generator control unit 98 or 100. However, this is undesirable. If both were to be so connected, then the effects of these switches would be confused. The receiver

synchro 128 related to one group of winches 20, and the corresponding switches 140, 142, 146 and 148 can be expected to be proper for only one stage set; and consequently no two groups of winches should be operated from the same alternator concurrently with the synchro-operated control switches shown. Where two groups of winches are to be operated, they are connected to the two different power supplies provided. In that connection each one controls its own power supply, as described above. The selective control means for connecting the switches 140, 142, 144 and 146 to one or the other of the control units 98 and 100 take the form of push buttons in the illustrative example, although naturally suitable rotary switches with the proper number of decks, or push buttons and multi-contact relays having the interlocks like those provided for the illustrated push-button example, may be substituted if desired.

A pair of push buttons 150 and 152 are shown, having a centrally pivoted interlock 154 that prevents both of the push buttons 150 and 152 from being simultaneously depressed. These push buttons have a neutral position, and each one of them also a depressed position. Push button 150 simultaneously closes five sets of contacts 150a, 150b, 150c, 150d and 150e. Similarly five sets of contacts are operated by push button 152, namely, contacts 152a, 152b, 152c, 152d and 152e. The push buttons 250 and 252 at the right in Fig. 9 operate corresponding switch contacts, and any added number of push buttons and switches 350 and 352, etc., may be provided, corresponding to the number of stage sets that are to be handled separately. By means of a diagrammatically illustrated interlock 151, only one push button 150—250—350 can be depressed at any one time, and a like interlock 153 prevents more than one push button 152—252—352 from being depressed at any one time. This avoids the difficulty described above, of having plural sets of winches on one alternator at one time, with conflicting rate and stop rate controls.

The upper set of contacts 150a and 152a are provided for controlling the relays 80 and 86 (Fig. 9a) for connecting motor 52 to the selected lines 82 or 88 of generator 84 or 90. Wires 155 and 157 from these two relays 80 and 86 extend to a two-prong plug 156 that fits a receptacle 158 forming part of a patch panel in the control console. When plug 156 is inserted in receptacle 158, assuming that all other controls are appropriately effective, motor 52 will operate with the power delivered by the selected generator, under control of the rate and limit switches controlled by the receiver servo 128. Any number of additional motors not having transmitter synchros (or not using them) can be coordinated with motor 52 simply by plugging their plugs 156 into additional parallel-connected receptacles 158 as illustrated, which will accordingly energize one of the control relays 86 or 88 of those additional motors 52 and thereby connect the additional motors to the same generator for coordinated operation. Thus, closing up contacts 150a will cause relay 86 to connect its related motor 52 to wires 82 of generator 84 whereas closing contacts 152a will cause relay 80 to connect that motor 52 to bus 88 of generator 90. All other winch motors plugged into the same group of parallel-connected receptacles 158 will also be connected to the same generator and will be subject to the same rate variation and interruption of drive, in accordance with the controlled power delivered by that generator.

The safety lever 154 makes it impossible for both contacts 150a and 152a to be simultaneously closed. This would be damaging (in the absence of safety devices in series with the relay contacts of relays 80 and 86) for in that event both generators would be connected simultaneously to one of the motors and accordingly both generators would be connected to each other. Push button control lever 154 prevents this.

Push button 150 when depressed connects "Up" limit

switch 140 via wire 160 through contacts 150b and wire 162 to a bus 164. This is connected to "Up" contacts 124a of the direction switch operates the "Up" motor starter 116 of alternator 84 provided that the "Up" contacts 124a are closed (as shown). As previously mentioned, the direction control switch 124 is moved from its normal neutral position only after depression of a selected push button 150 (etc.). This closes contacts 150a and causes the relays 80 (or 86) to connect their respective motors 52 to the supply lines 82 (or 88), before those lines are energized and thus spares relays 80 and 86 from the more severe duty of a motor starter. Closing of "Up" contacts 124a operates the motor starter 116 and energizes lines 82 of generator 84.

Operation of push button 150 similarly closes contacts 150e, to complete a circuit from "Down" limit switch 142, via wire 166 and wire 168 to bus 170 and to "Down" contacts 124b of directional switch 124. In similar fashion to the "Up" control circuit just described, this causes closing of the "Down" motor starter 118 and energizes lines 82 to operate all winch motors thrown onto lines 82 by their relays 80 under control of patch panel 156—158 and contacts 150a.

If either "Up" limit contacts 140 or "Down" limit contacts 142 should be open when the group of winches are to be driven down or up, respectively, that fact would not disturb the manner of operation described. The limit contacts 140, 142 are in series only with the related contacts of the directional switch 124.

Operation of push button 152 closes contacts 152b and 152e, and connects switches 140 and 142, respectively, to direction control contacts 126a and 126b that are effective to throw alternator 90 on its lines 88. The operational details and effects are no different from that described in connection with contacts 150b and 150e, and need not be reviewed further.

Push button 150 is also effective to close contacts 150c thereby to connect the open side of contacts 144a and 146a via wires 172 and 174 to "minimum speed" connection 106 of a control 98 for alternator 84. At the same time, push button 150 closes contacts 150d to complete a circuit extending from control wire 102 of unit 98 (Fig. 9c) through contacts 146b (Fig. 9b) and contacts 144b extending via wire 176 and contacts 150d to wire 178 to bus 180 and the slide contacts of potentiometer 112. If either of contacts 144b or 146b is open, as when the related winches are at one extreme position, this circuit to potentiometer 112 is broken. Moreover other contacts 144a or 146a would then be closed, connecting "CTL" wire 102 via wire 172, contacts 150c and lead 174 to the "minimum" speed wire 106 of the dynamic coupling control 98. This means that starting with dog 134 at either extreme, the scenery handling operation will proceed slowly until the respective switch 144 or 146 is thrown to the position shown in the drawing, after which high speed operation will commence; and it will continue until automatically reduced by dog 134 operating the other rate control switch 146 or 144.

If push button 152 were operated in place of push button 150, the same series of connections would be established, linking contacts 140, 142, 144 and 146 with the control circuits of alternator 90, and repetition of detailed description is evidently unnecessary. It is evident, accordingly, that any push button 150—250—350 is effective to connect its related switches 140, 142, 144 and 146 in control relation to alternator 84 while push buttons 152—252—352 are effective to connect its related contacts like 140, 142, 144, 146 to the control circuits of alternator 90. Each push button throws its related group of winch motors to the lines from such alternator, by virtue of push button contacts 150a or 152a (etc.), its related patch panel 156—158, and relay 80 or 86 (but not both, because of the safety interlock 154 that bars closure of both contacts 150a and 152a).

The general operation of the control system may now

be reviewed. Operation of the console push buttons 150, 152, etc. control selection of winch motors in groups as determined by the patch panels 156—158, and the push buttons also determine which alternator will supply power to each selected group of motors. Thereafter operation of the direction control switches 124 and 126 will connect the alternators to the respective three-wire lines via selected motor starters 116, 118, 120 and 122 to operate the groups of motors in the desired directions. In the console, even though one "stop" switch 140 or 142 is open, the selected groups of motors will operate if the power phasing is right for operating the winch (and the receiver synchro) toward the opposite limit. At first the rate of operation is low, but after the travelling dog 134 leaves the limit switch 140 or 142 and reverses the adjacent switch 144 or 146, the rate of operation changes to high. This rate continues until dog 134 reaches the opposite rate control switch, whereupon the speed drops; and the drive stops when the opposite stop switch is operated by dog 134. The rate may be low, at two inches per second, when the sets come close to the level of the stage, and a high speed, of two feet per second for example, may be in effect outside the top and bottom limits of travel of the set. Scale 147 opposite dog 134, displayed on the console, indicates at the control point where the set is during its travel. Units 94 and 96 are advantageously of such design as to cushion any abrupt rate change.

In setting up a new series of sets, lines 26 are connected to them from individual winches. The winch motors are operated individually by plugging the related plug 156 into a patch panel, depressing a related push button, and throwing a direction control switch. This manually controlled operation of a single motor at a time is carried on for each motor having a line connected to a scenery unit until all the supporting lines 26 are taut, with the set at stage level. It makes no difference at this stage which motors 52 have synchros. This is because the switch 130 of the synchro related to the push button circuit used at this time is open and dog 134 can be set at a mean point by manipulating handle 135, thereby to enable full-speed operation of the motors or operation of the motors at any lower desired speed under control of manually adjusted potentiometers 112 and 114. During this initial operation switch 124 or 126 can be reversed to reverse operation of a supporting line 26, and operation can be quickly interrupted by moving switch 124 or 126 to its neutral position so as to deenergize both starters 116 and 118 or 120 and 122, depending on which switch 124 or 126 is used.

When a group of individual lines have been adjusted so that they all share the load of the set, all the plugs 156 of that group are plugged into the patch panel sockets 158. With switch 130 of the related synchro still open, the set can be carefully lowered to the stage, with manual rate control. Then switch base 138 can be adjusted. Similarly, switch base 136 can be adjusted to locate the set at the proper height in the fly-loft. Switch 130 can then be closed, putting the synchro of one winch motor of a group in control of the group of motors. Other motors of this group may or may not have synchros; but if they do, their switches 130 will be left open. Ordinarily about one winch motor in two or three will have a synchro, while the console may have only enough capacity (as to receiver synchros, push buttons, etc.) to handle a predetermined number of groups of winch motors. In such circumstances, any transmitter synchro of a winch motor can be plug-connected to any receiver synchro in the console, to function in controlling a group of motors.

Where two alternators are used, two groups of winch motors can be automatically operated simultaneously, in opposite directions if it is desired to raise one set and lower another. Both can be used to raise or to lower two scenery units, in which case each rate-and-stop control functions automatically for its set without disturbing the

preset automatic operation of the other. Moreover, in the event of alternator failure, the remaining alternator can be operated as a stand-by unit, losing only the advantage of simultaneous operation of differently controlled groups of winch motors.

Numerous variations in detail and varied application of the novel features of the described illustrated embodiment of the invention will occur to those skilled in the art, and certain novel features may be employed without taking advantage of others; and consequently the invention in its various aspects should be broadly construed, in accordance with its full spirit and scope.

What I claim is:

1. Apparatus for operating groups of lines supporting respective stage sets, wherein any selected group is to raise one stage set and at the same time another selected group is to lower another stage set, including an individual winch having a reversible electric drive motor for each line in each group of lines, two controllable sources of electric power, selective means for connecting one group of said electric motors to one of said sources for controlled operation thereby, said connecting means causing the selected group of drive motors to operate all the corresponding winches to wind in the lines and raise the stage set supported thereby, and further selective means for connecting another group of said motors to the other of said sources for controlled operation thereby, said further connecting means causing said other group of electric motors to operate the corresponding winches to unwind the related group of lines and lower the stage set connected thereto.

2. Apparatus for operating groups of supporting lines connected to respective stage sets, wherein any selected group of lines is to raise one set at the same time that another selected group is to lower another set, including winch means having reversible electric drive means for each group of lines, the electric drive means of each group of lines including plural synchronous motors, two controllable sources of electric power, and selective means for connecting the electric drive means of any desired one of said groups of lines to one of said sources, said one source being related to the selected electric drive means to operate its winch means to raise its set, and for connecting the electric drive means of any other desired group of lines to the other of said sources, said other source being related to said other electric drive means to operate its winch means to lower its set.

3. Apparatus for operating groups of supporting lines connected to respective stage sets, wherein any selected group of lines is to raise one set at the same time that another selected group is to lower another set, including winch means having reversible electric drive means including plural interconnected and electrically interlocked motors for each group of lines, two controllable sources of electric power, and selective means for connecting the electric drive means of any desired one of said groups of lines to one of said sources, said one source being related to the selected electric drive means to operate its winch means to raise its set, and for connecting the electric drive means of any other desired group of lines to the other of said sources, said other source being related to said other electric drive means to operate its winch means to lower its set, said selective connecting means including multiple selectors, and interlock means between the selectors preventing any selected drive means from being connected simultaneously to both said sources.

4. Apparatus for operating scenery supporting lines, wherein a selected line is to raise a set at the same time that another selected line is to lower another set, including for each line a winch having a reversible electric motor, two separately controllable sources of electric power, and selective means for connecting any desired one of said motors to one of said sources for raising its set and for connecting another desired one of said motors to the other of said sources to lower its set.

5. Apparatus for operating scenery-supporting lines, including a winch individual to each line having a reversible electric drive motor, two sources of electric power controllable separately for determining speed and direction of motor operation, and selective means for connecting any desired one of said motors to either one of said sources, whereby any selected winch can be operated either to raise or lower its stage set at the same time that any other selected winch can be operated independently to raise or lower its stage set.

6. Apparatus for operating scenery-supporting lines, including a winch individual to each line having reversible electric drive means, two sources of electric power controllable separately for determining speed and direction of operation of said electric drive means, and selective means for connecting any desired one of said drive means to either one of said sources, whereby any selected winch can be operated either to raise or lower its stage set at the same time that any other selected winch can be operated independently to raise or lower its stage set, said selective means including multiple selectors having interlock means therebetween preventing any selected one of said drive means from being connected simultaneously to both said sources.

7. Apparatus for operating groups of lines supporting respective stage sets, wherein two sets are to be operated concurrently but independently as to direction, speed and duration, including an individual winch having a reversible electric drive motor for each line in each group of lines, two controllable sources of electric power, selective means for connecting any desired group of said electric motors to either one of said sources for operation in either selected direction, and further selective means for connecting any other desired group of said motors to the other of said sources for operation in either selected direction.

8. In a theatre, plural stage sets each having a corresponding group of supporting lines, an individual self-locking winch having a reversible electric drive motor for each line, and means for selectively connecting the motors together in groups for conjoint operation so that the group of lines supporting each stage set can be operated by any accessible winches conjointly operated by their coordinated motors.

9. Apparatus for operating groups of lines supporting respective stage sets including for each line an individual winch having a reversible electric drive motor, and means for selectively connecting the motors together in groups for conjoint operation so that any group of lines of a stage set can be operated by any desired winches.

10. Apparatus for operating groups of lines supporting respective stage sets including an individual self-locking winch having a reversible electric drive motor for each line, and means for selectively connecting the motors together in groups for conjoint operation so that any group of lines of a stage set can be operated by any desired winches and selective means for energizing any desired group of said electric motors to raise or lower a corresponding stage set.

11. In a theatre, plural stage sets each having a corresponding group of supporting lines, including an individual winch and a reversible electric motor for each of said lines, switch means operable to connect concurrently any selected group of said motors to a common source of power, power control means coordinated with each group of motors to control the operation thereof at different elevations of the stage set, and selective control means effective for simultaneously connecting said power control means in control relation to said source of power and for selectively operating said switch means for connecting the corresponding group of said electric motors to the source of power.

12. Apparatus for operating groups of lines connected to respective stage sets, including an individual winch and a reversible electric motor for each of said lines,

one winch of each group including a transmitter synchro, a receiver synchro at a remote control station, means controlling said source of power operable by said receiver synchro to reduce speed when the corresponding group of winches has driven its stage set to a point approaching a limit of travel of that stage set, and selective control means effective for simultaneously connecting said power source control means in control relation to said source of power and for selectively connecting the corresponding group of said electric motors to the source of power.

13. Apparatus for operating groups of lines connected to respective stage sets, wherein any selected group is to operate one stage set and each other group is to operate another respective stage set, including an individual winch and a reversible electric motor for each of said lines, means for connecting any desired group of said motors together, and a common motor starter for connecting any selected group of motors to a source of power.

14. Scenery handling apparatus in a theatre or the like having a stage, scenery units suspended above the stage, lines secured to said scenery units at spaced points thereof, and individual winches distributed aloft, each line extending from a scenery unit to one of said winches, and electrical coordinating means for the winches controlling each scenery unit.

15. Scenery handling apparatus in a theatre or the like having a stage, scenery units suspended above the stage, lines secured to said scenery units at spaced points thereof, laterally adjustably mounted sheaves located vertically above said spaced points, and individual electrically operated winches distributed at fixed locations aloft, each line extending from a scenery unit vertically to one of said sheaves and thence laterally to one of said winches.

16. Scenery handling apparatus in a theatre or the like having a stage, scenery units suspended above the stage, lines secured to said scenery units at spaced points thereof, laterally adjustably positioned, sheaves located vertically above said spaced points, and individual electrically operated winches distributed aloft at fixed locations, each line extending from a scenery unit vertically to one of said sheaves and thence laterally to one of said winches, each of said winches including line guiding means at a fixed position in relation to the corresponding sheave and a cylindrical drum provided with both rotational drive means and drive means for shifting the drum in relation to the line guiding means, said drive means being related to each other to maintain the winding point of the drum opposite said line guiding means.

17. Scenery handling apparatus in a theatre or the like having a stage, scenery units suspended above the stage, lines secured to said scenery units at spaced points thereof, laterally adjustably positioned sheaves located vertically above said spaced points, and individual winches distributed aloft at fixed locations, each line extending from a scenery unit vertically to one of said sheaves and thence laterally to one of said winches, each of said winches including line guiding means at a fixed elevation and a vertical-axis drum provided with both rotational and vertical-travel drive means related to maintain the winding point of the drum opposite said line guiding means, plural synchronous motors for operating the winches of each stage set and electrical coordinating means for interconnecting the motors identified with each stage set for concurrent coordinate movement.

18. Scenery handling apparatus in a theater or the like having a stage, scenery units suspended above the stage, and lines secured to said scenery units at spaced points thereof, said apparatus including a laterally adjustably positioned sheave located vertically above one of said

spaced points, an individual winch having a fixed location aloft, a line extending from said one point vertically to said sheave and thence laterally to said winch, said winch including line guiding means at a fixed elevation, and a drum provided with both rotational and axial-travel drive means related to maintain the winding point of the drum opposite said line guiding means.

19. Scenery handling apparatus in a theatre or the like having a stage, scenery units suspended above the stage, and lines secured to said scenery units at spaced points thereof, said apparatus including a horizontally adjustably mounted sheave located vertically above one of said spaced points, an individual winch having a fixed location aloft, a line extending from said one point vertically to said sheave and thence laterally to said winch, said winch including line guiding means at a fixed elevation, and a drum provided with both rotational and axial-travel drive means related to maintain the winding point of the drum opposite said line guiding means, 15 said sheave and said winch each having a swivel bearing with a vertical axis for automatically aligning the winch and the sheave along the line extending therebetween.

20. Scenery handling apparatus in a theatre or the like having a stage, scenery units suspended above the stage, lines secured to said scenery units at spaced points thereof, horizontally adjustable sheaves located vertically above said spaced points, and individual winches distributed aloft, each line extending from a scenery unit vertically to one of said sheaves and thence laterally to a corresponding one of said winches, the winches that operate the lines from each scenery unit constituting a group, and plural electrically interlocked motors for each group of winches.

21. Scenery handling apparatus in a theatre or the like having a stage and scenery units suspended by lines above the stage, said apparatus including a line-guiding sheave vertically above the place where each line is secured to a scenery unit, and a winch individual to each line mounted aloft, each winch having line guide means defining a winding point, said line guide means and said sheaves having vertical swivel bearings for automatic alignment thereof along a scenery-suspending line extending therebetween.

22. Scenery handling apparatus in a theatre or the like having a stage and scenery units suspended by lines above the stage, said apparatus including a line-guiding sheave vertically above the place where each line is secured to a scenery unit, and a winch individual to each line, the winches being mounted aloft, each winch having line guide means defining a winding point, said line guide means and said sheaves having vertical swivel bearings for automatic alignment of a sheave and the line guide means of the related winch along a scenery-suspending line extending therebetween, the lines from each scenery unit constituting a group of lines and the corresponding winches constituting a group of winches, and electrically coordinated drive means for each group of winches.

23. Scenery handling apparatus in a theatre or the like having a stage, including a series of winches distributed aloft at fixed locations about the stage, each winch having a separate reversible electric motor, sheaves mounted for horizontal adjustment to respective selected positions directly above the stage, and lines extending from said winches over corresponding sheaves to scenery units suspended from those lines.

24. Scenery handling apparatus in a theatre or the like having a stage, including a series of electric-motor driven winches distributed aloft and including a row of said winches across the rear of the stage, scenery-supporting lines extending from said winches and secured to scenery at spaced points thereof, line-guiding sheaves 70 respectively above said points, front-to-rear extending

elongated members at a level above said winches, each elongated member having a close-spaced series of formations for securing sheaves thereto at any of numerous locations.

25. Scenery handling apparatus in a theatre or the like having a stage, including a series of electric-motor driven winches distributed aloft and including a row of said winches across the rear of the stage, scenery-supporting lines extending from said winches and secured to scenery at spaced points thereof, line-guiding sheaves respectively above said points, front-to-rear extending elongated members at a level above said winches, each elongated member having a close-spaced series of formations for securing sheaves thereto at any of numerous locations, and a grid spaced sufficiently below said winches and said sheaves to enable operating personnel to set up said winches, lines and sheaves as variously required.

26. In a theatre having a stage and flies above the stage for storing movable units of scenery, scenery handling apparatus including multiple lines connected to a unit of scenery at respective spaced-apart points thereof, modular sheave locating and supporting means above the stage, sheaves carried by said means, winches at spaced-apart locations about the flies, said lines extending over the respective sheaves to respective winches, individual synchronous electric motor drives for said winches, and common energizing and control means for coordinately operating said motors.

27. In a theatre having a stage and flies above the stage for storing movable units of scenery, scenery handling equipment including a series of winches distributed about said flies, lines from said winches to said units of scenery, synchronous electric motors for said winches, and common control means for each group of said winches connected by lines to scenery elements of a given stage set, there being as many groups of winches as there are stage sets.

28. In a theatre having a stage and flies above the stage for keeping a series of stage sets available, scenery handling equipment including regularly distributed winches along the rear and sides of the flies, lines extending from selected winches to supporting points of a stage set, said selected winches constituting a group of winches and there being as many groups of winches as there are independently operable stage sets, individual synchronous electric motors for said winches and common control means for the motors of each group of winches, said control means including a controlled-frequency alternating current source.

29. In a theatre or the like, scenery handling equipment including gridiron, multiple flying sets, including sets of non-flat form and having supporting lines extending vertically from out-of-line points along the top edges thereof, adjustable sheave supports spaced above the gridiron, and sheaves distributed thereon in accordance with the distribution of lines from the stage sets, a multiplicity of winches fixed at positions distributed about said gridiron, each line extending to a respective winch, and a coordinated drive means for each group of winches to which lines extend from correlated portions of a stage set, there being at least as many winches as lines and as many groups of winches as independently operable stage sets.

30. Scenery handling apparatus in a theatre or the like having a stage, scenery units suspended above the stage, a group of lines secured to each scenery unit at spaced points thereof, a plurality of winches distributed aloft, each line extending to a separate one of said winches, an individual electric motor for each of said winches, the winches and motors related to each group of lines constituting a group of winches and a group of motors, respectively, switch means to connect any desired group of motors to a source of power for con-

joint operation to shift the related scenery unit, a transmitter synchro coupled to one winch of each group, plural receiver synchros at a remote control station, each receiver synchro being connected to a corresponding

5 transmitter synchro, and means controlling the operation of said electric motors, said control means being operable by said receiver synchro to limit operation of said connected group of motors when the corresponding scenery unit has been carried by its group of winches to

10 a preset limit of travel of that scenery unit.

31. Scenery handling apparatus in a theater or the like having a stage, including a series of winches distributed aloft, each winch having a separate electric motor and a supporting line extending from each winch 15 over guide means to a respective point of suspension of a scenery unit, a power line extending past said electric motors, plural relays operable to connect respective motors to said power line, said relays having control lines to a remote control point and being connected to each other in groups at a patch panel at said remote control point, the relays of each group being related to the lines of each group 20 and selective means for operating any one group of said relays thereby to connect the related motors of that group to the power line for operating the scenery-suspending lines of the related motor-operated winches.

32. Scenery handling apparatus in a theater or the like having a stage, including a series of winches distributed aloft, each winch having a separate electric

35 motor and a supporting line extending from each winch over guide means to a respective point of suspension of a scenery unit, a power line extending past said electric motors, plural relays assembled to said electric motors and operable to connect the respective motors to said power line, said relays having control lines to a remote control point and being connected to each other in groups at a patch panel at said remote control point, the relays of each group being related to the lines of each group

40 supporting a scenery unit, and selective means for operating any one group of said relays thereby to connect the related motors of that group to the power line for operating the scenery-suspending lines of the related motor-operated winches, one of said electric motors of each group having a transmitter synchro coupled thereto, a receiver synchro at the remote control station connected to the respective transmitter synchro of each group of motors, there being as many patch panels as there are receiver synchros, a controllable source of power connected to said power line, and control means operated

55 by said receiver synchros for controlling said power source automatically in accordance with the position of the corresponding scenery unit relative to its upper and lower limits, said selective means for operating said groups of relays additionally including means for connecting the control means of each receiver synchro in control relation to said source of power.

33. Apparatus for operating groups of lines connected to respective stage sets, including an individual winch

60 and a reversible electric motor for each line, means effecting coordinate operation of each group of motors connected by supporting lines to individual stage sets, one winch in each coordinated group having a transmitter synchro mechanically connected thereto, plural receiver synchros at a remote control station connected re-

65 spectively to the transmitter synchros, said remote control station being at a vantage point in view of the stage, and control means for said motors including rate control means individual to each receiver synchro and operable thereby to reduce motor speed when the stage set

70 related thereto approaches either its lowermost or uppermost limit, and manually operable motor speed control means effective throughout the range when said rate control switches are not in effect.

34. Apparatus for operating groups of lines connected

to respective stage sets, including an individual self-locking winch having a reversible electric motor for each scenery-supporting line, two controllable sources of power, pairs of relays at said motors for connecting each motor to either of said sources, plural means for interconnecting said relays in groups for enabling connection of said motors in corresponding groups to either of said controllable sources, the motors thus grouped corresponding to the lines connected to said stage sets, respectively, a transmitter synchro coupled to one winch of each group for coordinate operation therewith, a receiver synchro at a remote control station connected to each respective transmitter synchro, control means operated by each receiver synchro in relation to the winches related thereto and including "up" rate and limit switches and "down" rate and limit switches, and group selecting means, said last-named means including a pair of selectors for each group of motors and, correspondingly, for each stage set, one selector of each pair having contacts for energizing those interconnected relays of each group of motors that connect such motors to one of said sources of power simultaneously and said one selector also having contacts for connecting the related rate and limit switches of that group of motors in control relation to said one source of power and the other selector of each pair of selectors having contacts for energizing those interconnected relays of each group of motors that connect such motors to the other of said sources of power simultaneously, said other selector of each pair of selectors also having contacts for connecting the related rate and limit switches of that group of motors in control relation to said other source of power, one of said sources having respective direction control connections to the grouped motors connected thereto to operate said groups of lines for controllably raising the related stage set and the other of the sources of power having direction control connections to the motors connected thereto to lower the related stage set under independent control, whereby any desired group of motors can be selectively energized to raise one stage set and another selected group of motors can be operated at the same time to lower another selected stage set, other stage sets not selected being operable subsequently for raising or lowering under control of its related pair of selectors.

35. Scenery handling apparatus in a theatre or the like in accordance with claim 23, including a grid spaced below said sheaves by a distance to enable operating personnel to adjust said sheaves and arrange said lines thereover.

36. In a theatre having a stage and flies above the stage for keeping a series of stage sets readily available, and set-handling apparatus including a series of winches distributed aloft at fixed locations, said winches having uniform-diameter drums and means providing a constant winding point, sheaves above the stage, adjustable locating and supporting means for the sheaves, lines extending from said winches over said sheaves and vertically downward to respective suspension points of the sets, 5 said sheaves having vertical-axis swivel bearings for aligning each sheave with a corresponding winding point of one of said winches, a synchronous alternating-current motor for each winch, a controlled-frequency alternating current power source and a power line extending from said power source adjacent to the motors of said winches, grouping means operable to connect the motors of each stage set to the power line concurrently, and frequency control means for said power source to provide controlled-speed coordinated operation of the lines supporting each stage set when the synchronous motors of said winches are connected to said power line.
37. Scenery handling apparatus in a theatre or the like having stage sets suspended above the stage and having supporting lines secured thereto at spaced points, 25 sheaves adjustably located vertically above said spaced points, a series of winches distributed aloft at fixed locations, each of said winches having a synchronous electric motor, the lines of each stage set extending over respective ones of said sheaves to said winches and arranged to be operated coordinately thereby, the electric motors which operate the winches and the supporting lines of each stage set constituting a group of motors, a pair of power lines extending past said electric motors, selective means operable to connect a selected group of said motors 30 to one of said power lines and to connect another selected group of said motors to another of said lines, a pair of variable-frequency alternating-current power supplies for said power lines, separate means for adjusting the frequencies of said power supplies, and respective control 35 means coupled to the motors of each selected group and operable coordinately therewith for separately adjusting the respective frequencies of the alternating-current power supplies in accordance with the elevation, relative to the stage, of each stage set being operated.
